TO UNITED STATES ENVELOPE COMPANY, OF SPRINGFIELD, MASSACHUSETTS, A
CORPORATION OF MAINE.

ENVELOP-MACHINE.

1,252,969.

Specification of Letters Patent.

Patented Jan. 8, 1918.

Original application filed October 7, 1913, Serial No. 793,852. Divided and this application filed June 7, 1915. Serial No. 32,542.

To all whom it may concern:

Be it known that I, JAMES E. TREVOR, a subject of the King of Great Britain, residing at Hartford, in the county of Hartford and State of Connecticut, have invented new and useful Improvements in Envelop-Machines, of which the following is a specification.

This invention (divided out of co-pending application Serial No. 793,852, filed Oct. 7, 1913, as divisional application), relates to an improvement in mechanism for delivering envelops from a drying chain as ordinarily used in a rotary envelop machine.

The object of the invention is to provide improved delivery mechanism to take the envelop from the drying chain in an improved and positive manner. Other objects of the invention will appear in the detailed description and annexed claim.

With these objects in view the invention is shown in one preferred embodiment thereof in the accompanying drawings in which:

Figure 1 shows a rear elevation of a portion of an envelop machine embodying the invention only so much being shown as is necessary to an understanding thereof;

Fig. 2 is a side sectional view taken on the line 2—2 of Fig. 1; and

Fig. 3 is a diagrammatic view of one way in which the nippers of the transporting device may operate.

In the drawings, A represents the frame of the machine. The envelops l', formed except for the "last fold" or the fold known as the seal flap, are delivered from the part of the machine not shown around a roll mounted on the shaft a of Fig. 2. Up to this point in the forming of the envelop, it has been held in the machine by rolls but, as the envelop is delivered from the roll on the shaft a, it, for the first time, is released from the holding rolls. The machine for forming the envelop up to this delivery point is well-known by those skilled in the art and does not concern the present invention in such a way as to make an explanation of that part of the machine necessary.

As the envelop is delivered from the rolls, it falls downwardly on to the belt f. This belt passes around guide rolls mounted on the shafts b, g, and e, as shown in Fig. 2, and is operated from shaft e. The width of the belt f is proportioned to the surface of

the envelop which comes in contact therewith in such a way that the frictional engagement of the belt with the envelop will be sufficient to move the latter into the exact folding position in a positive manner. When the envelop is delivered on to the belt, the only thing that remains in forming the envelop is to fold over the seal flap 14. In order to hold the envelop for the folding operation, a brass-plate h is provided which is mounted to oscillate on the shaft g, being mounted on the latter by means of a pair of ears, as shown in Fig. 2. The shaft g is rocked by a link motion i operated from a suitable cam (not shown) connected with a power shaft. When the envelop is delivered onto the belt, plate h has been moved in a clockwise direction, as shown in dotted lines, in order to form together with the surface of the belt f an open mouth to receive the envelop. At the upper end of the plate h, there is a folding blade k. When the envelop has been received by the belt f and drawn downwardly, the plate h is swung in a counter-clockwise direction so that it lies parallel to the upper portion of the belt and the lower edge of the envelop abuts a stop 25 under the plate h to position it. The folding blade k presses the envelop against the stationary plate 13 along which the roll d travels. This roll d is mounted on a short arm extending from the outer end of the arm c and the arm is provided with a spring, not shown, tending to press it toward the arm c, the latter movement being prevented by the stationary plate 13 and the folding blade k. The shaft 15 is rocked at the proper time by a cam, not shown, connected with any suitable power shaft of the main-frame. This movement is so communicated to the arm c that, when the roll d is on the plate 13, the envelop will be fed over said roll to the belt and, when the envelop and folding plate h have been properly positioned, the roll d will come against the seal flap of the envelop and fold it over the folding blade k. The folding roll d then retires to allow the envelop to be transported from the folding mechanism. The plate h swings in a clockwise direction to the dotted line position to again form an open mouth with the belt f. During this swinging movement, the transporting nippers 9, which are carried on a link p, grasp the edges of the en-

velop, as shown in Fig. 1. The belt *f* and the plate *h* are made narrow enough to allow the nippers to take hold of any size envelop which the machine may be making. 5 These nippers are arranged to close on the envelop and transport it from the folding mechanism to the drying chain.

The operation of transferring nippers of the class indicated in Figs. 1 and 2 is well 10 known by those skilled in the art. It is not thought necessary to show them in full detail in said figures. In Fig. 3 a diagrammatic showing of a simple nipper mechanism is shown which could be used if desired. The nippers 9 are each pivoted on a relatively stationary angle piece 32, and each nipper comprises a bell-crank lever one arm of which operates to bind the envelop against the part 32 and the other to act as 15 a stop-arm as shown. A leaf-spring 31 on part 32 bears against a part of the nipper extending rearwardly from its pivot and acts to hold the nipper in either one of its two positions to which it may be moved in 20 an obvious manner. It will be understood that all these parts may be carried by the link *p* in Fig. 2. When the link *p* moves in position for the nippers to grasp the envelop, the arms of the two nippers are pushed 25 against stationary pins 34 to throw the nippers from open to closed position. The springs 31 bearing against the projections of the nippers as they pass across centers will act to snap and hold them in the desired 30 position. Similarly when the link *p* moves in position for the nippers to open and release the envelop, the other arms of the nippers are pushed against pins 33 and the nippers are sprung open. This is one of the 35 well-known nipper constructions which may be used as well as others.

The drying chain, a portion only of which is shown, is mounted on the frame A to travel vertically, the lower end of its travel 40 passing around a suitable sprocket on the shaft 8. When the carrying fingers *v* pass around the sprocket, they are opened in a well-known manner, as shown in Fig. 2, and the envelop is inserted one on each carrying 45 finger just before it closes with relation to the one preceding it. In order to transport the envelop from the folding mechanism to the carrying fingers, the following mechanism is provided: an arm *q* is keyed to the 50 shaft *n* mounted in the main-frame and is pivoted to the upper end of the link *p* as shown in Fig. 2. A second arm *o* is pivoted on the outer end of the bracket 16 and is pivoted to the lower end of the link *p*. The 55 shaft *n* is oscillated by means of a link motion *m* which is operated by a crank mounted on the shaft *e* as clearly shown in Fig. 2. This oscillation of the shaft *n* moves the links *o*, *q*, and *p* from the full line position 60 to the dotted line positions, the upper one

being the delivery position for the transporting mechanism. The nippers 9 are designed to release the envelops when in the delivery position. The links *o*, *q*, and *p* can then move to the full line position again. 70 During the transportation of the envelop from the folding mechanism to the drying chain, the seal flap 14 is apt to open, and, to prevent this, an arm 10 is provided which rocks with shaft *n*. Its purpose is clearly 75 shown in the dotted line position shown in Fig. 2. As the envelop is released by the nippers one of the carrying fingers *v* moves under the envelop and carries it upwardly. The driving chain is operated in a step by 80 step manner each step taking place while an envelop is being delivered to the closing carrying finger.

These carrying fingers are each designed to carry any length envelop within a certain 85 range and where long envelops are being made the ends of the envelop last placed in the chain are liable to sag downwardly in such a manner that the following envelop being delivered to the following finger will 90 strike the edges of the sagging envelop and interfere with the proper transporting operation. In order to prevent this interference, two arms *u* are mounted on the shaft *t*, the arms *u* being so distanced on the shaft *t*, 95 that, if the latter is turned clockwise, they will come up under the ends of the envelop and bend them upwardly to prevent sagging. This shaft *t* is operated by means of a cam *r* mounted on the shaft *n*, having a 100 link connection *s*, with the shaft *t*, as shown. The operations of the arms *u* are timed with respect to the feeding operations so that, when an envelop is being delivered, the arms will be in the position shown in full lines 105 in Fig. 2, and after the envelop has been delivered, they will move to the dotted line position shown in said figure. This insures a proper feed operation without interference due to long envelops. 110

When the envelops have traveled around the drying chain so that the gum on the seal flap has been properly dried, they are delivered by the following mechanism: The outer edges of the envelop extending beyond 115 transporting fingers *v* come to rest upon plate 3 (supported by a bracket from the frame). A pusher *x* (see Fig. 1) is operated by any suitable mechanism connected with a power shaft of the main frame to engage one end of the envelop and push it from its position on the plate 3 in the drying chain into an oscillating discharge device B, pivoted at point 1. This device is oscillated from the full line position to the 120 dotted line position by the link *z* which is connected to any suitable cam on one of the power shafts. In the dotted line position the envelop enters between suitably distanced guide-plates 4 and *y*. The forward 125 130

end of the upper guide plate γ as seen in Fig. 1, is bent upwardly to provide a ready entrance for the envelop. After the envelop has been received by the discharge device B, the latter is oscillated to the full line position shown in Fig. 1 and a reciprocating discharge plate 12 having a hook 11 on the upper end thereof moves into position so that the hook lies back of the upper edge of the envelop and the discharge plate 12 is then moved downwardly so that the hook 11 will move the envelop from the discharge device B toward the counting mechanism not shown. On account of the very rapid operation of a machine of this character, the hook 11 is liable to operate without removing the envelop from the discharge device. In order to prevent this, I provide special means for holding the envelop in such a position that the hook 11 will invariably engage the upper edge of the envelop to remove it from the discharge device. This mechanism comprises a shaft 5 (see Fig. 2) on which are mounted two radial fingers 6 and 7, which are angularly positioned with respect to one another held by spring 27 in position shown in Fig. 2. The shaft 5 is mounted in a bracket fastened to the discharge device B, and, when the latter is moved from the position shown in Fig. 2 to the full line position shown in Fig. 1, the finger 6 will engage the stationary rod 17 which will cause the shaft 5 to turn and the holding finger 7 to be moved against the envelop, as shown in Fig. 1. The finger 7 then presses against the envelop a short distance from the upper edge thereof, and, with the envelop held in this fashion, the hook 11, which slides upwardly along the lower surface of the envelop after it passes by the finger 7, will press the edge of the envelop upwardly, but the instant the hook 11 has reached the full line position shown the edge of the envelop will immediately spring into position (due to its own resiliency) to be engaged by hook 11 in the discharge operation.

It is not absolutely necessary to rock the device B as described for it can remain in full line position shown. In this case, the envelops would fall one by one into the open mouth formed by guides γ and 4. The holding finger 7 will then be operated by any suitable operating means rather than by the means described.

Referring to the "last fold" mechanism, in order to prevent any springing back of the envelop after striking stop 25, spring 26 is provided, which on the closing down of plate δ will rest lightly against the envelop.

What I claim is:

In an envelop machine, the combination with a drying chain for drying the gum on the seal flap of the envelop, of means to remove the envelops one by one from the chain and a reciprocable delivery mechanism arranged to engage the edge of the envelop after it leaves the chain to move it out of the way of the following envelop, and a device to hold the edge of the envelop into position to be engaged by the said delivery mechanism.
